UNITED STATES PATENT OFFICE.

OSCAR F. FORSBERG, OF YONKERS, NEW YORK, ASSIGNOR TO WESTERN ELECTRIC COMPANY, OF NEW YORK, N. Y., A CORPORATION OF ILLINOIS.

TERMINAL MOUNTING FOR METALLIC SPOOLS.

1,163,904.

Specification of Letters Patent. Patented Dec. 14, 1915.

Application filed December 7, 1914. Serial No. 875,808.

To all whom it may concern:

Be it known that I, OSCAR F. FORSBERG, a citizen of the United States, residing at Yonkers, in the county of Westchester and 5 State of New York, have invented certain new and useful Improvements in Terminal Mountings for Metallic Spools, of which the following is a full, clear, concise, and exact description.

10 This invention relates to metallic spools for electromagnets, and more particularly to a terminal mounting for such structures.

The object of this invention is to provide a new and improved form of terminal 15 mounting for metallic spools in which the terminals may be rigidly secured to a metallic spool-head in a convenient manner with all parts well insulated and without interference with the winding space.

20 In accordance with the general features of this invention the spool-head is provided on one face with a raised portion and a corresponding depressed portion in its opposite face, and a terminal securing member extends through this raised portion and has 25 its inner end secured within the depressed portion preferably by riveting. Insulating members are secured to the opposite faces of the spool-head adjacent the raised and depressed portion by the terminal securing member. Means are also provided for clamping the terminal against rotation.

In the drawings—Figure 1 is a view in elevation of a portion of a spool-head with 35 terminals attached thereto; Fig. 2 is a sectional view taken upon line 2—2 of Fig. 1; Fig. 3 is a sectional view taken upon line 3—3 of Fig. 1; and Fig. 4 is a view in side elevation of a spool embodying this invention.

As shown in the drawings 3 designates a winding located between metallic spool-heads 4 and 5 of a metal spool. One portion of the spool-head 5 is struck up to form a 45 raised portion 6 on its outer face, with a corresponding depressed portion 7 on its inner face. Extending through openings 8, 8 in this raised portion are tubular members or eyelets 9, 9. The outer end of each of 50 the tubular members is provided with a head 11, and the inner end thereof is upset or riveted as shown at 12, this upset portion being within the depressed portion 7 and below the normal inner surface of the spool-head 5. An insulating strip 13 is inserted

in the depressed portion 7 between the face of the spool-head and the upset ends 12 of the tubular members 9, and insulating strips 15 and 16 are inserted between the heads 11, 11 and the raised portion 6. A flat terminal 60 member 20, having a projecting lug 21 thereon, is clamped between the head 11 of each of the tubular members or eyelets 9 and the insulating member 16. The lug 21 extends into an opening or slot 22 in the insulating 65 member to prevent the rotation of said terminal.

By means of this construction there is produced a terminal mounting of few and simple parts, which may be readily secured 70 to a metallic spool-head, and in which all of the parts will be rigid and well insulated. Moreover, the inner ends of the terminals will not interfere with the winding space of the coil, nor be likely to short-circuit the 75 adjacent turns of the winding.

What is claimed is:

1. The combination with a metallic spool-head having a raised portion on one face, and a corresponding depressed portion in 80 the opposite face of a terminal, a securing member for said terminal extending through said raised portion, said member being secured at its inner end within said depressed portion, insulating members secured to the 85 opposite faces of said spool-head adjacent said raised and depressed portion by said terminal securing member for insulating said terminal from said spool-head, and co-operating means between said terminal and 90 the insulating means for preventing the rotation of said terminal.

2. The combination with a metallic spool-head having a raised portion on one face thereof and a corresponding depressed portion 95 in the opposite face thereof, of a terminal, a securing member for said terminal extending through said raised portion and secured at its inner end within said depressed portion, insulating members secured 100 to the opposite faces of said spool-head adjacent said raised and depressed portion by said terminal securing member, and a projection upon said terminal engaging the insulating members upon the said raised 105 portion to prevent the rotation of said terminal.

3. The combination with a metallic spool-head having a raised portion on the outer face thereof, and a corresponding depressed 110

portion in the inner face thereof, of a tubular member extending through said raised portion and having its inner end riveted within the depressed portion of the inner 5 face of said spool-head, a head formed upon the outer end of said tubular member, insulating members secured within said depressed portion and upon said raised portion by said riveted member, a terminal 10 clamped between the outer insulating member and the head of said tubular member,

and a projecting locking member on said terminal engaging the insulating members upon said raised portion to prevent the rotation of the terminal.

15

In witness whereof, I hereunto subscribe my name this 4th day of December A. D., 1914.

OSCAR F. FORSBERG.
